UNITED STATES PATENT OFFICE.

ALEXANDER GRANT McGREGOR, OF WARREN, ARIZONA.

ART OF FEEDING POWDERED COAL TO BLAST FURNACES.

Application filed September 29, 1920. Serial No. 413,595.

To all whom it may concern:

Be it known that I, ALEXANDER G. McGREGOR, a citizen of the United States, residing at Warren, in the county of Cochise and 5 State of Arizona, have invented or discovered certain new and useful Improvements in the Art of Feeding Powdered Coal to Blast Furnaces, of which the following is a specification, reference being had therein 10 to the accompanying drawings.

This invention relates to an improvement in the art of feeding powdered coal to blast furnaces, and has for its object a method which, as compared with the methods at 15 present in use, will be more economical in the use of power, will require less space around the furnace, and be more readily installed, and which will provide a more flexible and reliable means for distributing 20 the coal to each and every tuyère of the furnace than the method now in use.

The method at present most generally in use for feeding the coal into the tuyères of blast furnaces is by feeding the powdered 25 coal from the supply hopper by a screw conveyor. This screw conveyor is arranged so as to distribute the coal into from one to six or eight individual pipes, each leading to an air injector. The air injector produces a 30 suction, drawing the coal into it, and discharges the mixture of coal and air into the furnace tuyère.

As the pressure of the blast air entering 35 the furnaces is from 2 to 3 pounds per square inch, it is usual, in practicing the present method, to use air at a pressure of some 10 pounds greater than the blast air at the furnaces, for operating the injector, and to provide this air at higher pressure considerable 40 power is required.

As the usual blast furnace may have from 40 to 140 tuyères, a number of coal hoppers with their feed screws and injectors would be required, and would make a complicated 45 and bothersome installation which must be placed as close to the furnace as possible where the space is limited, and where it would interfere more or less with the other equipment and operations about the furnace. 50 Such systems are not always reliable in delivering the desired amount of coal to each tuyère.

In accordance with the present invention the powdered coal is delivered and distributed 55 to each tuyère of a blast furnace by means of an air circulating and distributing

system, similar to the systems which are now being used in plants where coal is distributed to a number of heating furnaces in the same building or plant. In practising the 60 present invention powdered coal is fed into the suction air pipe of a centrifugal fan blower. In the fan the coal and air are intimately mixed and discharged, under a pressure of approximately 6 ozs. per square 65 inch, the discharge being into a fuel pipe main which, through suitable branches, supplies a mixture of air and coal to the various furnace burners.

Sufficient velocity is maintained in the 70 main to prevent the coal from settling and clogging it. To accomplish this, the main is preferably in the form of a loop communicating with a return pipe and carries more 75 air and fuel than is delivered to the furnaces, so that a certain amount of the fuel-laden air in the main passes by all the branch pipes and is returned to the fuel and air supply for the fan.

Automatic means may be provided for 80 regulating the amount of coal fed into the system, so that the proper mixture of powdered coal and air will be maintained in the main and its branches, regardless of the amount being actually consumed by the furnace. Such a means and system is described 85 in U. S. Patent No. 1,206,112, issued to A. A. Holbeck, November 28, 1916.

In accordance with the present invention a fuel supply main, containing a mixture of 90 coal and air under sufficient pressure, extends around on both sides of the blast furnace, similar to the bustle pipe which furnishes the air through the various short branches to the tuyères of the furnace. In 95 the same way the mixture of coal and air is drawn from the fuel main through short pipes to the furnace tuyères in the practice of the present invention, and suitable valves may be provided in the short branch pipes 100 so that the amount of the fuel mixture going to each tuyère may be regulated.

A coal distributing system, similar to those now in use, as described, could be used for delivering coal into the fuel mains 105 through branch pipes, and into the tuyères of a blast furnace in the manner suggested. But as the pressure of the blast in the tuyères of a copper blast furnace, for instance, is usually maintained at some pressure between 24 ozs. and 40 ozs. per square 110 inch, the fan which delivers the mixture of

coal and air would have to maintain a pressure at least 6 ozs. higher than the blast pressure, so that the mixture of air and coal delivered by the fan would flow through the main and branches at a high velocity and into the tuyères against the furnace blast pressure.

To deliver the mixture of fuel and air against a pressure of say 30 ozs., the runner 10 of the fan would necessarily have to operate at a very much higher velocity than is required for delivering at a pressure of only 6 ozs. per square inch. This would result in excessive wear of the fan, due to the particles of coal impinging against the interior parts of the fan at the high velocity.

In the present invention this difficulty is overcome by taking the suction air for the fan from the blast furnace main. In this 20 way the fan is only required to boost the furnace main pressure about 6 ozs., and it will not be required to run any faster than fans are now running in connection with the ordinary low pressure air coal distributing systems, and the wear on the fan will be no greater.

In the accompanying drawings, which, it will be understood, are more or less diagrammatic, Fig. 1 is an elevation illustrating an apparatus by which the invention may be carried into effect, and Fig. 2 is a plan view of the same.

Referring to the drawings, 12 denotes a blast furnace having tuyères 13, through 30 which the powdered coal is to be fed into the furnace by means of air under pressure passing through pipes 14, the outlets of which join the outlets of the fuel pipes 15, the air pipes 14 communicating with the main air blast pipe 16 through the bustle pipes 16^a, and the fuel pipes 15 communicating with the fuel feed pipe 17. The powdered fuel is discharged from the fuel inlet pipe 18 to a collector or separator 19 which empties into a bin 20 having at its bottom an outlet 21 through which the powdered coal is discharged into a pipe 22 in which is located a screw conveyor 23 which feeds the fuel into the pipe 24 communicating with a booster blower fan 25 which, in turn, communicates with the fuel feed pipe 17. The air and powdered coal are thoroughly mixed by the fan 25.

The main air blast pipe 16 is provided 55 with a branch pipe 26 opening into an air flow meter 27 through which the air passes into a pipe 28 communicating with the pipe 24, so that air from the main air blast pipe 16 is delivered to the fan at a pressure of 60 say 3 pounds to the square inch, or the blast furnace pressure; and this pressure is augmented by the fan 25 by only about 6 ounces to develop the necessary pressure for feeding the powdered fuel into the furnace 65 through the fuel feed pipe 17.

Surrounding the furnace 12 is a looped fuel header pipe 29 into which the powdered fuel is discharged from the feed pipe 17, and with which the fuel pipes 15 communicate, the said header pipe being merely a 70 continuation of said feed pipe. Preferably communicating with the said header pipe 29 is a return pipe 30 which communicates with the collector or separator 19 so that any surplus fuel not discharged into the 75 furnaces through the tuyères is returned to the fuel supply and the surplus air is again returned to the fan.

The branch pipe 26 is preferably provided with a damper or valve 31 by which the air supply from the main air pipe may be cut off when desired.

The speed of motor 39 and screw feeder 23 which it drives is regulated by means of the rheostat 32, which is controlled by the 85 piston 36 in the air flow meter 27, the said piston being connected by the rod 37 with the lever 34 pivoted on a support 35, said lever being in turn connected with the rheostat regulating lever 33; so that if the 90 amount of fuel and air delivered to the furnace is increased more air will be drawn in through the flow meter and the speed of screw feeder will be automatically increased. In the same way, if the air and 95 coal admitted to the furnace is reduced, the speed of the screw feeding the coal will be reduced, thus keeping the ratio of coal to air in the mixture constant. The motor 39 is electrically connected with the rheostat 100 32 by conductors 38.

From the foregoing it will be understood that the normal air pressure, when the fan 25 is not running, is practically the same in the fuel inlet pipe 17 as in the main air blast 105 pipe 16, and that an increased pressure of only about 6 ozs. is required in the said fuel inlet pipe 17, to be developed by the fan 25, in order to properly feed the fuel into the furnace.

The coal will preferably be delivered to the bin 20 by an air transport system through the pipe 18 and collector 19 for the reason that the bin 20 will be under a pressure equal to the main air blast pressure, and to avoid interruption in the operation, the coal would have to be delivered against the bin pressure. The collector or separator 19 is vented to the pipe 26 through the pipe 42 which allows the air in the return pipe 30 to be delivered to pipe 26; and also allows whatever air is required in delivering the coal to the bin 20 by the air transport system, to be delivered to the fan. The additional air required by the fan is 115 drawn from the main air blast pipe 16.

The furnace 12 may be provided with an outlet stack 40 and tap hole 41 at its bottom, etc., as usual.

It will be understood that, if thought de- 130

sirable, check valves may be installed in the tuyère pipes between the tuyères and the bustle pipes to prevent the coal from being blown back into the bustle pipes in case the tuyères become clogged. It will also be understood that the powdered coal may be fed into the discharge of the fan 25 instead of into the suction, as indicated by the drawings.

- 10 It is preferred that the return pipe 30 discharge through the separator 19, so as to collect the surplus powdered fuel which is then discharged into the bin 20, although the surplus air could be discharged into the atmosphere; but by discharging the air in the return pipe into a pipe or chamber having connection with the blast main, or to the suction of the fan which has approximately the blast pressure in it, the air is 15 again used and the power required to compress it up to the blast pressure originally is not wasted.

The invention is not to be understood as being limited to the details of the particular apparatus herein shown and described and which somewhat conventionally illustrates an apparatus by which the invention may be carried into effect, as the means by which the invention may be practiced may be varied 20 widely, as will be understood by those skilled in the art.

Some of the advantages of the arrangement described may be mentioned as follows:

- 25 Much less power is required for forcing the fuel into the tuyères than is used in the injector scheme now in use for delivering powdered coal into blast furnace tuyères.

As a more efficient means than a centrifugal fan blower is generally used for delivering the blast air under pressure to blast furnaces, by providing a fan to boost this pressure, by only a few ounces, as described, less power on the whole will be required 30 than if a fan were used to draw the coal and air in at atmospheric pressure and compress it up to 6 ozs. higher than the main air blast pressure. This would be similar to the systems now in use for heating furnaces except the fan would be called upon to develop much more pressure, and the wear of the fan on account of the higher velocity of the rotating part would be greater.

In practice, the blast air pressure varies 35 from time to time, due to pulsation, variation in the speed of the prime mover, and a variation in the amount of air delivered to the furnace or furnaces, and if the compressed air for delivering the coal to the blast furnace tuyères is compressed by an independent means, there will also be variations in its pressure, due to variation in the speed of the motor driving it and due to variations in the amount of air being used.

40 By using a fan running at a constant

speed, which receives its suction from the air blast main and merely boosts this pressure up a few ounces, to furnish the air for feeding the coal into the furnace tuyères, it will be apparent that a very simple means 45 is provided in the present invention for maintaining a practically constant difference in pressure between the fuel air and the blast air.

In accordance with the present invention 50 all moving mechanism may be remote from the furnace, where it will not be injured by, or be in the way of the operations about the furnace.

While the sketches and description herein 55 relate more or less to copper blast furnaces, it will be understood that the invention is also applicable to lead and iron and other blast furnaces.

As hereinbefore stated, to prevent the 60 powdered coal from settling in and thus clogging the fuel feed pipe 17, more air and coal are fed into said pipe than is delivered into the furnace and the surplus is returned to the separator 19 through the pipe 30.

Owing to the fact that the closed fuel bin 65 20 into which the fuel is fed through the pipe 18 by air pressure, is in communication with the main air blast pipe 16 through the pipes 26 and 42, a pressure higher than 70 atmospheric pressure, and approximately equal to the pressure in said main blast pipe, will be maintained in said bin. Thus as no air pressure in the system will be vented to the atmosphere there is no loss of pressure 75 which would have to be replaced by additional power.

Having thus described my invention I claim and desire to secure by Letters Patent:—

1. The herein-described method of delivering powdered fuel to a blast furnace, consisting in introducing the said fuel into the furnace through a fuel pipe or passageway communicating with the main air blast 80 pipe or passageway, and increasing the air pressure in the said fuel pipe or passageway to a sufficient extent to enable the fuel to be forced into the furnace against the air pressure developed therein from the said main air blast pipe.

2. An apparatus for delivering powdered fuel to a blast furnace, comprising a main air blast pipe, a fuel feed pipe leading to the furnace, and a booster fan communicating 85 with the said main air blast pipe and discharging into said fuel supply pipe.

3. An apparatus for delivering powdered fuel to a blast furnace, comprising the combination with a furnace provided with 90 tuyères, of a main blast furnace pipe, branch air pipes communicating with said main blast pipe and leading to the furnace tuyères, a fuel supply pipe carrying a mixture of air and powdered fuel and also com- 95

municating with said tuyeres through branch pipes, and means for creating an air pressure in said fuel supply pipe higher than the blast pressure; whereby the fuel mixture may be discharged into said tuyères against the blast pressure of the furnace.

4. An apparatus for delivering powdered fuel to a blast furnace, comprising a main air blast pipe leading to the furnace, a fuel feed pipe communicating with the said main air blast pipe so as to receive air under pressure from said main air blast pipe, and a booster fan communicating with the said main air blast pipe and with the said fuel feed pipe and serving to increase the air pressure in said fuel feed above that received from said main air blast pipe.

5. An apparatus for delivering powdered fuel to a blast furnace, comprising a main air blast pipe leading to the furnace, a fuel feed pipe communicating with the said main air blast pipe so as to receive air under pressure from said main air blast pipe, a booster fan communicating with the said main air blast pipe and with the said fuel feed pipe, and serving to increase the air pressure in the said fuel feed above that received from said main air blast pipe, and a pipe for returning the surplus fuel from the pipes at the furnace to the fuel bin or the fuel entrance part of the apparatus.

6. An apparatus for delivering powdered coal to a blast furnace comprising a main air blast pipe, a fuel feed pipe, means for causing said fuel pipe to deliver fuel to a furnace under a pressure higher than the furnace blast pressure and adapted to carry more air and fuel than is discharged into the furnace, a closed fuel supply bin, means for creating a pressure in said bin higher than atmospheric pressure, and a return or circulating pipe communicating with said fuel feed pipe and said bin so that the surplus fuel may be returned to the source of supply.

7. An apparatus for delivering powdered coal to a blast furnace comprising a main air blast pipe, a fuel feed pipe, means for causing said fuel pipe to deliver fuel to a furnace under a pressure higher than the furnace blast pressure and adapted to carry more air and fuel than is discharged into the furnace, a closed fuel supply bin, means for connecting said bin with said main air blast pipe and thereby creating a pressure in said bin approximately equal to the pressure in said main air blast pipe, and a return or circulating pipe communicating with said fuel feed pipe and said bin so that the surplus fuel may be returned to the source of supply.

In testimony whereof I affix my signature.
ALEXANDER GRANT McGREGOR.
